UNITED STATES PATENT OFFICE

EDWARD R. KAST, OF PEARL RIVER, NEW YORK, ASSIGNOR TO DEXTER FOLDER COMPANY, OF NEW YORK, N. Y., A CORPORATION OF NEW YORK

SHEET FEEDING APPARATUS

Application filed March 8, 1928. Serial No. 280,123.

The present invention is an improvement in what is known as continuous feeders, that is to say, feeders in which the sheets are fed from a bank in fanned-out relation, which bank can be continuously replenished without stopping the operation of the machine.

The advantages of such a continuous feeder are that the pile can be continuously replenished without stopping the operation of the machine, when applied to a printing press or other device; it occupies less floor space, and when feeding tacky stock, that is, stock that has had one or more colors applied thereto, the separate sheets can be more readily fed to the press or folder than is the case where the sheets are stacked in piles. This is due to the fact that in the continuous feeder the replenished sheets are preliminarily separated when loaded on the upper feed-board and also because in the feeding off position on the lower feed-board there is only a limited number of super-imposed sheets.

In the continuous feeders heretofore used there is generally employed combing wheels that act to separate and forward the sheet to the drop rollers. The use of these combing wheels is objectionable for the reason that it is necessary to adjust them to engage the sheets between the printed matter in order to prevent smearing or smutting of the stock, and frequently the color applied to the sheet is so solidly distributed that there is no blank space for engagement by the combing wheels. In addition, there are grades of stock which will inevitably be marred by the action of the combing wheels.

Furthermore, difficulty has been encountered in properly maintaining the forward feed of sheets of varying characteristics, some of which under the action of the combing wheels move forwardly more freely and rapidly than others, and hence either automatic or other means for regulating the tension on the rear edge of the fanned-out bank is necessary. This condition made it difficult with this type of machine acting on stock of varying thicknesses and characteristics to accurately and certainly feed off only one sheet at a time.

Furthermore, with feeders of this type it is

extremely difficult and at times impossible to feed sheets whose length in the line of feed is considerably greater than its width, for example, twice as great. The reason for this is that it is difficult to adjust the cut-out mechanism to control the combing of the sheets on account of the fact that the resistance between the uppermost sheet and the sheet thereunder is so great. Feeders of this type have heretofore required so-called cut-out mechanism for raising the combing wheels off of the bank of paper being fed, the cut-out mechanism being operated by the forward edge of the sheet engaging the cut-out pendulum. This pendulum through connections of greater or less complexity operates to automatically raise the combing wheels. In addition, in feeders of this type as heretofore used, the combing wheels operate not only to feed forward the topmost sheet, but also a number of underlying sheets, the combing action of the wheels progressively decreasing downwardly through the thickness of the fanned-out bank. Under these conditions, if two of the sheets were stuck together, there would be no separation of these two sheets but they would be fed forward to the drop rollers.

Furthermore, in feeders of this type the feed of the bank is determined by the length of the comb and the period of engagement of the combing wheels with the bank. This involves the objection that complicated mechanism is required to advance the bank through this control.

A further objection that has been heretofore encountered in connection with continuous feeders is that it was necessary to maintain the fanned-out bank under the combing wheels or other mechanism for feeding off the topmost sheet at a predetermined thickness, or to provide means for compensating for variations in thickness of the fanned-out bank under the combing wheels or other feed off means.

The object of the present invention is to retain all of the benefits of the continuous type of feeder and at the same time eliminate all of the objections heretofore noted. In short, by the present invention, the sheets of

100

whatever size or dimensions will be accurately and certainly separated and fed one at a time whatever the quality or condition of the stock without any smearing or smutting of the stock; and this is effected by a greatly simplified construction in which the customary tail drag, combing wheels and cut-out mechanism for raising the combing wheels are eliminated.

10 Generally stated, the objects of the invention are attained by providing in a continuous feeder means for positively separating and winding the topmost sheet to be fed from the next underlying sheet in the fanned-out bank, the sheets in the fanned-out bank being positively held against movement with the topmost sheet as the latter is being fed to the drop rollers. The feeding means for forwarding the sheet are of the suction type 15 and as they have no sliding or frictional engagement with the sheet, as was had by the combing wheels, the sheet, regardless of the condition or quality of the stock and whether printed or blank and of whatever size or 20 dimensions, is picked up by the suction feeder and fed forwardly without injuring or marring, or smearing or smutting.

This suction forwarding mechanism may be so constructed if desired or necessary that 25 it will always align the forward edge of each sheet in a predetermined alinement with respect to the drop rollers or other mechanism to which the sheet is being forwarded, and this is the case even though successive 30 sheets might be out of alinement to a greater or lesser degree with the drop rollers. Instead of controlling the forward feed of the bank by the means for feeding off the sheets, this movement of the bank is effected by a 35 simple feeler that is positioned to engage the upper surface of the forward edge of the foremost advancing sheet. If the foremost sheet is not engaged by the feeler the bank is forwarded—if it is engaged the bank is 40 not forwarded.

With respect to the preliminary separation of the sheets of the fanned-out bank, it is desirable that the sheets shall be operated on uniformly by the separating mechanism 45 and, to this end, I provide a separating mechanism that engages the rear edge of the topmost sheet with a predetermined pressure and at a predetermined angle whatever the thickness of the bank under the separating 50 elements and whatever the condition of the stock.

The forwarding mechanism is preferably constituted by a pair of forwarding devices, one being located near each lateral margin 55 of the sheet, and if desired means may be provided for stopping the action of each or both of the forwarders when the advancing edge of the sheet has reached a predetermined point. By this construction it will be appreciated that one forwarder on one side of

the sheet may stop its action before the action of the other forwarder is stopped, to the end that the sheet will always be properly aligned at a predetermined position with respect to the drop rollers.

The bank advancing means is preferably provided with a feeler that engages the top of the sheet along the front edge, if one is present. In my construction there is preferably provided a tongue or plate provided with a recess that underlies the forward edge of the fanned-out bank. If a sheet is interposed between the feeler and the tongue, the bank advancing means will not be operated, but if any sheet or sheets are not present under the feeler the same will project into the recess in the tongue and this further movement of the feeler will operate through suitable connections to advance the fanned-out bank.

The invention will be more readily understood by reference to the accompanying drawings, illustrating one embodiment of the inventive idea, and in which—

Referring to the drawings wherein like reference numerals indicate like parts, the feed board and associated mechanism and the bank advancing means will first be described:

*Feed boards, belts and bank advancing means,
Figs. 1, 2, 2a, 3 and 5*

On the usual or any customary supports 30 is mounted the main frame of the feeder including uprights or side frames 31 and 32 at the forward end of the feeder and upright side-frames 33 and 34 at the rear of the feeder. Side-frames 31 and 32 are connected by a hollow transverse tube 35 and a stay shaft 36. The rear frames 33 and 34 are connected by a roller shaft 37, stay rods 38 and 39, and roller shafts 40 and 41. The front and rear frames are connected by longitudinal bars 42, and 43. (Figs. 2 and 5.)

Carried by the tube 35 is a plurality of supports 44 on which the forward end of the upper feed board 33' is mounted and secured in any desired manner.

As here shown a channel iron 45 is fastened to the underside of said feed board by screws 46, and the channel iron and board is then secured to the supports 44 by screws 47. The rear end of the upper feed board is similarly mounted on the stay rod 39 through supports 48, channel iron 49 and screws 50 and 51. The lower feed board 52 is of the conventional type.

The belts that are associated with the upper feed board are indicated by the numeral 53, as here shown four such belts being employed. These belts pass around a roller 54 suitably mounted in the forward end of the feed board and around the drum 55 at the rear of the feed board, the upper reach of

the belt engaging the upper surface of the feed board 33' as usual. A second series of belts 56 constitutes the movable throat through which the sheets pass from the upper to the lower feed board. These belts pass 70 around a roller 57 carried in a swinging frame 58 pivoted at 59, which frame may be swung to the dotted line position shown in Fig. 2 when it is desired to open the throat. The belts 56 also pass around tightener roller 60 75 and around a tube 61 mounted on the stay shaft 41. Suitable tightening means are associated with this series of belts, such as the spring 62, one end of which is secured to a sliding rod 63 on which the roller 60 is carried, the other end of said spring being connected to a hook member 64. An adjusting mechanism of this or any suitable type is preferably provided for each belt 56 of this series. 85

A third series of belts is associated with the lower feed board. As here shown, five such belts 65 are employed, though any desired or suitable number may be used. The upper reach of each of these belts engages the 90 upper surface of the lower feed board 52, and said belts pass around a series of rollers mounted on shaft 66 at the forward end of the feeder and around a series of rollers 67 carried by a tape-tightener mechanism 68 at 95 the rear of the feeder.

The bank of sheets is advanced toward the press or other device to be fed by suitable means including a sprocket wheel 69 mounted on shaft 66 around which passes a sprocket 100 chain 70, said chain also passing around a sprocket wheel 71 mounted on a stud 72 carried in frame 33. Compounded with sprocket wheel 71 is a spur gear 73 that meshes with an idler gear 74 which in turn meshes with 105 a gear 75 that drives a large gear 76 carried on the drum 55. When the shaft 66 is revolved the lower belts 65 will be positively advanced and the drum 55 will be rotated, thus frictionally driving the belts 53 associated with the upper feed board, the belts 56 being moved through the advancing paper. These belts can be manually moved in either direction by means of a hand crank 77 provided with a pinion 78 that meshes with the 110 gear 75. A clutch connection 79 is interposed between the handle 77 and the pinion 78 so that the handle may be readily engaged or disengaged.

The control of the feed of the fanned-out 120 bank of sheets is effected by means of a feeler 80 which is adjustable vertically on an arm 81 carried on a shaft 82 having bearings in side frame 31 and a bracket 83 positioned on the valve casing. The shaft 82 projects outwardly through the frame 31 and carries a depending link 84 which has a pin and slot connection 85, with a dog 86 pivoted at 87 on the side frame 31. On the shaft 66 is loosely mounted a carrier 88 on which is pivoted a 125 130

detent 89. On said shaft is also loosely mounted a pawl carrier 90 on which the pawl 91 is suitably pivoted. One end of a link 92 is connected to the upper end of the pawl carrier 90, and the other end of said link is connected to a rotating disc 93 mounted on cam shaft 94. A spring 95 (Fig. 1) is interposed between the carrier 88 and the carrier 90 and holds them separated, one end of said spring being connected to a pin 96 on the pawl carrier 90 and the opposite end of the spring being connected to a pin 97 on the detent carrier 88. Through the connections described, the two carriers 88 and 90 reciprocate as a unit in the normal or non-feeding position, that is to say when the pawl 91 is out of engagement with the ratchet 99. In the event that the feeler 80 fails to engage a sheet, said feeler passes through an opening 100 in a plate 101, and this further movement of the feeler causes a counterclockwise rotation of the shaft 82 which causes the nose of the dog 86, which theretofore has been riding on the upper surface of the detent 89, to engage the recess 102 in said detent, thus arresting the movement of the carrier 88. The movement of the carrier 90, however, continues, and as the carrier 90 moves toward the carrier 88 the pressure or expanding action of the spring 95 on the pawl 91 is relieved and the pawl 91 drops into engagement with the ratchet 99 and a feeding movement is imparted to said ratchet, thus moving forward the bank of fanned-out sheets. Excessive movement of the dog 86 in a clockwise direction (Figs. 1, 2 and 2a) is prevented by a lug 102' on carrier 88. The connection between the pawl 91, the carrier 90 and the carrier 88 whereby this release of the pawl is obtained so that it may engage the ratchet 99 under such conditions is as follows:

Projecting laterally from the pawl 91 is a pin 103 that passes through an elongated opening 104 in the carrier 90. This pin engages in the recess of a hook member 105 secured to or integral with the carrier 88. Inasmuch as the spring 95 normally tends to hold the members 88 and 90 apart, it will be seen that the pin 103 is held in an elevated position in the slot 104 by frictional engagement with the surface of the hook 105. When, however, the movement of the member 88 is arrested as before described, and the member 90 moves toward the left, as shown in Fig. 2, and toward the carrier 88, the spring pressure on the pawl 91 is relieved and accordingly the pin 103 is no longer pressed against the recess in the hook 105 by the spring, and therefore the pawl 91 is permitted to drop into engagement with the ratchet. As soon as the feeler next engages a sheet, the parts will automatically resume the position shown in Fig. 2, the pin 103 again assuming its elevated position and holding the pawl 91 out of engagement with the ratchet.

It will be seen that the feeler 80 is periodically elevated either when the nose of the dog 86 is riding on the upper surface of the detent 89, as well as when the nose of the dog 86 has engaged the recess 102 of the detent, this elevation of the feeler 80 being effected whenever the links 84 and 86 are moved toward the left as seen in Fig. 2.

If desired, a second means for adjusting the position of the feeler 80 may be had through an arm 106 mounted on the shaft 82 and having associated therewith an adjusting screw 107 that passes through a bracket 108, a spring 109 being connected at one end to the arm 106 and at its other end to the bracket 108.

Drive and sheet separating mechanism, Figs. 1-8 inclusive, 22 and 23

The power for driving the movable parts of the machine is derived from any suitable means, as from the press or folder to which they are attached, which is the customary and usual method. However, for the purposes of illustration, the power is shown as being derived from a motor 110 mounted on a base 111 on which is also mounted a pump 112 that is connected to the armature of the motor by a sprocket chain 113 passing around sprocket wheel 114 on the motor shaft and 115 on the pump shaft. On the other end of the motor shaft is mounted a pulley 116 around which passes a belt 117, which belt also passes around a pulley 118 (Fig. 4) mounted on shaft 119 having bearings in the side frames 31 and 32. Shaft 119 has pinned thereto a pinion 120 that meshes with a gear 121 mounted on the cam shaft 94. It is from this cam shaft, through connections that will later be described, that the forwarder and valve mechanism is operated. On this cam shaft is mounted a pinion 122 that drives idler gears 123 and 124, the latter meshing with a gear 125 that is compounded with a bevel gear 126 that meshes with a corresponding bevel gear 127 mounted on a longitudinal shaft 128 that has bearing in a bracket 129 at one end and in a bracket 130 (Fig. 1) carried by the stay shaft 39. On this shaft 128 is keyed, near the rear end thereof, a bevel gear 131 which meshes with a bevel gear 132 carried on a stud 133 carried by a bracket 134 that is mounted on a square bar 135. Compounded with the bevel gear 132 is a second bevel gear 136 that meshes with corresponding bevel gears 137 and 138, the latter being pinned to shafts 139 and 140, said shafts having bearing in brackets 134 at their adjacent ends and in brackets 141 and 142 at their remote ends, said brackets 141 and 142 being also mounted on the square bar 135.

This square bar carries the sheet separating mechanisms, of which two are preferably employed. Inasmuch as these separating mechanisms are preferably identical in construc-

tion, adjustment and operation, it will only be necessary to describe one of them. Each separator unit is mounted and adjustable on the square bar 135. The separator unit includes an upper bracket 143 through which the bar 135 passes. A lower bracket 144 is connected to the upper bracket 143 by upwardly projecting pins 145 and 146 and a spline shaft 147, all of which project through said upper bracket 143. The spline shaft 147 carries a bevel pinion 148 that meshes with a corresponding bevel gear 149 mounted on a stub shaft 150 that is carried by a casing 151 secured to the upper bracket 143. At the other end this stub shaft 150 carries a bevel gear 152 that meshes with a bevel gear 153 on shaft 140. The lower end of the shaft 147 carries a bevel gear 154 that meshes with a bevel gear 155 on the cam shaft 156 of the separator unit. This cam shaft is mounted in depending arms 157 and 158 projecting from the lower bracket 144. On said cam shaft 156 is mounted a second bevel gear 159 that drives the combing wheel 160 through a shaft 161 that carries a bevel gear 162 meshing with the bevel gear 159. The construction and operation of this combing wheel is preferably the same as that disclosed in Christophel Patent No. 1,475,621. Likewise mounted on the cam shaft 156 is a cam 163 that operates to raise and lower the combing wheel 160. This elevation of the combing wheel by said cam is effected by means of a lever 164 pivoted at 165, said lever engaging under a roller 166 carried by a pin 167 secured at one end to an arm 168 which is carried by the combing wheel arm 169. The construction and operation of this mechanism for raising and lowering the combing wheel is also preferably that described and claimed in Christophel Patent No. 1,475,621. There is also carried by the cam shaft 156 a cam 170 that operates to raise and lower the foot clamp 171 through suitable connections, as more particularly described and shown in Christophel Patent No. 1,475,621. The sheet pick-up device 172, which is preferably of the suction type, is also controlled from the lever 164 as more fully described and shown in Christophel Patent No. 1,475,621. In short the construction and operation of the combing wheel, the foot clamp and the suction pick-up device are preferably of the type shown and described in Christophel Patent No. 1,475,621.

Loosely mounted on the cam shaft 156 for rotation thereon is a roller 173. This roller is preferably of conical configuration as shown in Fig. 5 for effective cooperation with the wedge shaped plate 174 that is inserted under the lateral marginal extremity of the fanned-out pile of sheets in a vertical plane beneath said conical roller. The cooperative action of the roller 173 and the wedge shaped plate 174 is to form a valley in the pile of fanned-out sheets, so that the operation of

the rotary combing wheel 160 is to straighten the topmost sheet across said valley as indicated in dotted lines in Fig. 5. The roller 173 is positioned rearwardly of the point at which the combing wheel 160 and the suction pick-up 172 engages the rear edge of the topmost sheet, the action of said roller 173 and said wedge shaped member 174 being effective to provide the necessary valley on the rear edge of the topmost sheet at the point that the sheet is engaged by the combing wheel 160 and the suction pick-up 172.

By the construction described, it will be appreciated that all of the sheet separating elements will operate on the pile of fanned-out sheets regardless of the thinness or thickness of the pile. In other words, the combing roller 160, the suction pick-up device 172 and the foot clamp 171 will engage the fanned-out sheets with the same efficiency and effect whether the fanned-out bank be composed of few sheets or many sheets; and this is due to the fact that the lower bracket 144 of the separator unit is a floating bracket and that the position of the various sheet separating elements is controlled by the roller 173 that floats on the fanned-out bank of sheets. It will be seen that if there are only a few sheets in the fanned-out bank, the roller 173 will lower with respect to the position that it would assume if there were many sheets under said roller. All of the operating parts of the sheet separating unit are carried by the lower bracket 144 that also carries the roller 173, this lower bracket 144 being connected to the relatively stationary upper bracket 143 through the rods 145 and 146 and spline shaft 147. Accordingly the sheet separating elements will act on the topmost sheet of the fanned-out bank in the same manner and with the same effect regardless of the number of sheets constituting the fanned-out bank.

In order to readily and effectively adjust the wedge shaped plates 174 under the lateral marginal extremities of piles of sheets of different widths, the lower feed board 52 is provided with a plurality of grooves 175 that have an inclined face 176 in which engages the rearward projecting edge of said wedge plate 174. This affords a clear and unobstructed passage to the sheets in their advance along the feed board 52 and the wedge shaped plate 174. The wedge shaped plates may be secured in any desired position of adjustment through the bracket arm 178, adjusting screw 179 and holes 180 in said feed board 52 in which said adjusting screw 179 may engage.

If for any reason, as when the feeder is first being loaded, it is desired to elevate the separator unit and hold it out of the way in elevated position, this can be readily effected by manipulating the hand wheel 181 (Fig. 6) carried by shaft 182 on which there is mounted

a gear 183 (shown in dotted lines in Fig. 6, and in full lines in Fig. 9) the gear 183 meshes with a rack 184 on the rod 146, so that rotation of the shaft 182 will elevate the lower bracket 144 of the separator unit, and raise all of the operative parts of the same to any desired position. The parts can be readily held in such elevated position by means of the set screw 185 (Fig. 6) which engages the shaft 182.

The provision of the differential constituted by the bevel gears illustrated in Fig. 8, makes it possible to adjust the two separator units independently of each other, and this is highly desirable in the event that the pile of fanned-out sheets should be presented to the separator units out of square, so that it became necessary for efficient and effective operation to position one separator unit in advance of a vertical plane passing through the other separator unit.

In order to effect this adjustment, it is necessary to move one end or the other of the square bar 135 which carries the various parts. As will be readily seen (Figs. 1, 19, 20 and 21) this bar is carried in arms 186 depending from longitudinally extending tubes 187 that have bearings at their rear ends in brackets 188 on the side frames 33 and 34, and bearings 189 in brackets (not shown) at their front ends. These tubes 187 are slotted at 190 (as clearly shown in Fig. 1) and through these slots project lugs 191 carried by a nut 192 that is traversed through said tube by a screw shaft 193 that is rotated by a bevel gear 194 carried thereon and meshing with a bevel gear 195 mounted on a spline shaft 196. The lugs 191 engage on either side of the depending arms 186 that carry the square bar 135. As clearly shown in Fig. 21 each end of the square bar is loosely mounted in one of the depending arms 186 by means of a screw-threaded pin 197, so that each end of said bar may move relatively to the corresponding depending arm 186.

The bevel gears 194 and 195 are enclosed in a casing 198 through a slot 199 in the top of which projects a handle 200 that is connected to the bevel gear 195. This bevel gear 195 is held yieldingly in mesh with gear 194 by means of the spring 201 (Fig. 19) reacting against collar 202 fixed on shaft 196. The gear 195 has a spline connection with the shaft 196 so that when the handle 200 is operated to disengage the gears 195 and 194, the shaft 196 may be rotated by either of the hand cranks 203, with which the shaft 196 is provided, so that only one of the threaded shafts 193 will be operated, the other remaining stationary so long as the operator holds the handle 200 in a position corresponding to the demeshing of the gears 194 and 195 on that side of the machine. Under these conditions, only one end of the square bar 135 will be moved longitudinally of the ma-

chine to effect the movement of the separator unit on that side of the machine with respect to the separator unit on the other side of the machine which stays stationary.

When one of the separator units is thus held stationary and the other is traversed to a new position of adjustment, this is effected without disturbing or in any way changing the driving connections of the differential 131, 132, 136, 137 and 138. As will be seen from an inspection of Fig. 8, the square bar 135 passes through a hollow member 134a of the bracket 134, and this hollow member carries a bearing surface 204 on which rests a bearing surface 205 carried by a bracket arm 206, through which arm the shaft 128 projects. This bracket arm is provided with an opening 207 through which the stud 133 projects, the bracket arm 206 being pinned to the stud 133 at 208. Accordingly any movement of one end of the square bar 135 with respect to its other end will effect a relative movement of the gears 132, 136, 137 and 138 with relation to the gear 131, the shaft 128 and the bracket arm 206, the latter under these conditions sliding on the bearing surface 204. It will be seen that such an adjustment will in no way effect a binding or strain on the shaft 128.

Having adjusted the two separator units to any desired position longitudinally of the machine and relatively to each other with respect to a vertical plane passing through one of them, means are provided for readily effecting a relative transverse adjustment of the separator units for sheets of any desired width or location on the lower feed board 52. Such lateral adjustment is effected by means of a pair of screw-threaded shafts 208 and 209. Each shaft (see Fig 5) has bearing at one end in a bracket 210 and bracket 134 at the other end. These screw-threaded shafts project through a corresponding screw-threaded lug 211 carried on the upper bracket 143 of the separator unit. Rotation of shafts 208 and 209 is effected by any suitable means as hand cranks 212 and 213, whereby lateral adjustment of the separator units with respect to each other is readily effected.

Sheet forwarding mechanism, Figs. 1, 4, 10, 11, 12, and 13

After the topmost sheet in the fanned-out bank has been separated, it is seized by the sheet forwarding mechanism and fed to the drop rollers 214. The sheet forwarding mechanism as herein disclosed is of the suction type. As here shown, two sheet forwarding devices are preferably employed, though under certain conditions only one may be necessary. When two sheet forwarding devices are employed, as in the embodiment of the invention herein disclosed, said devices, as well as hereinafter described control mechanism therefor, are preferably identical in

construction and operation. In the embodiment of the invention herein disclosed, it is therefore only necessary to describe in detail one forwarding device and control mechanism. The forwarding devices and control mechanism disclosed herein, are preferably constructed and operated as follows: As clearly shown in Fig. 10, an inverted U-shaped bracket 215 is fixed in any desired position of adjustment on the tube 35 by means of a set screw 216. The depending arms of this U-shaped bracket afford bearings for a shaft 217 on one end of which is mounted a pinion 218 that is oscillated by a sector 219 pivoted at 220, said sector being provided with an arm 221 (Fig. 4) carrying a roller 222 that engages in a cam groove 223 preferably formed in the face of gear 121. Through these connections a carriage 224 is reciprocated on a track bar 225 that is secured in any desired manner to one of the depending arms of the U-shaped bracket 215. The carriage 224 is slidably mounted on the track bar 225 on which carriage the suction forwarder 227 is mounted for vertical and reciprocating motion. A link 228 is connected at one end to the shaft 217 through means of a lever 229 and at the other end is connected at 230 to the carriage 224. This link is provided with a cam surface which is engaged by a roller 232 carried by an arm 233 pivoted at 234 to the carrier. The arm 233 carries a fork member 235 that engages the under surface of a collar 236 which is pinned to the tube 237 of the suction forwarder. The forwarder mechanism thus far described is of the general type shown and described in Christophe Patent No. 1,584,734.

It is sometimes desirable to provide means for straightening the sheet before it is presented to the drop rollers 214. It frequently happens that one side of the sheet will be presented between the feed roller 238 and the drop roller 214 while the other edge of the sheet is out of alignment. This condition is illustrated in Fig. 13 in which the full line position 239 shows the advancing edge of the sheet out of alignment, and the dotted line position 240 shows the advancing edge of the sheet in alignment. Means are provided whereby if the sheet approaches the feed roller 238 in the full line position, the sheet will be brought to the dotted line position before the drop rollers engage the same. To this end there is mounted on the carriage 224 a rack 241 which is screwed or otherwise fixedly secured thereto. The teeth of this rack may be in form of knurling, if desired, to permit of a close adjustment, as will hereinafter be more fully described. Carried on one of the fixed depending arms of the inverted U-shaped bracket 215 is a member 242 provided at its free end with arms 243 and 244. On the arm 243 is pivoted at 245 a dog 246 which is provided with a curved serrated

or knurled surface 247 that is adapted to engage the rack 241. Pivoted at 248 in the arm 244 is a pendulum provided with two arms 249 and 250, the arm 250 engaging the under surface of the dog 246 at 251 and supporting the same out of contact or engagement with the rack 241. The engaging end of the arm 250 is curved to provide a cam surface 252 that engages the dog for a purpose hereinafter described. The arm 249 normally projects downwardly into one of a plurality of grooves 253 and is held in this position until it is engaged by the advancing edge of the sheet. When so engaged, the arm 249 is elevated thus moving the arm 250 from under the dog 246 which then drops by gravity into engagement with the rack 241, at the same time that the tail of the dog by engagement with the surface 252 of the arm 250 swings the arm 249 clear of the sheet. If the sheet is out of alignment, and in the position indicated in full lines in Fig. 13, it will be understood that the arm of the stop mechanism for one forwarder will be engaged by the advancing edge of the sheet after the arm 249 of the stop mechanism for the other forwarder is so engaged. Accordingly it is necessary to provide means such that the actuating member for reciprocating one forwarder-carriage and the rack 241 secured thereto may continue its full stroke without further movement of the other forwarder-carriage and its rack 241. Accordingly such a structure is provided in the form of a yielding connection between the arm 229 and the link 228 of each forwarder carriage. This yielding connection may be of any suitable construction, but I prefer to use an elongated spring retainer 254 in which is engaged a roller 255. Normally this roller is held in recesses 256 provided on the two members of the spring retainer, said roller occupying said recesses until the dog 246 is lowered into engagement with the rack 241. When the movement of the rack 241 is thus stopped, the forward movement of the arm 229 will disengage the roller 255 from the recesses 256, the remainder of the movement of the arm 229 being an idle movement. When the carriage is to be retracted through the connections described, the roller 255 will re-enter the recesses 256 and be held therein. Further as the carriage is retracted, a laterally projecting pin 257 on the dog 246 is engaged by a curved surface 258 on the carriage which elevates the dog and permits the arm 250 to engage the underside thereof by any suitable means, as by gravity or by a flat spring 259. A pair of pins 260, 261, carried by the arm 243, limit the movement of the arm 250 in its forward and backward movement.

In order to confine the sheet so that it will always contact the arm 249 at the same point, a bifurcated guard plate 262 is provided, this guard plate being fastened to the arm 244,

and the arm 249 projecting between the bifurcated members.

Caliper mechanism, Figs. 10, 16, 17, 18 and 19

5 Preferably a caliper mechanism is employed which will operate to stop the feeding of the sheets in the event that more than one sheet is fed at the same time. To this end means are provided for automatically cutting off the suction to the sheet separators and the forwarders when the caliper is operated, and also to automatically lock the drop rollers in elevated position.

15 The caliper elements are preferably constituted by a lower rotary wheel 263 and an upper sheet engaging shoe 264. The wheel 263 is splined on shaft 265 and has a bearing in the caliper casting at 266 and also 20 in the frame 32 of the machine. This shaft 265 carries a gear 267 and is driven from shaft 119 through gears 268, 269 and 270, so that shaft 265 is continuously rotated in a counterclockwise direction, as seen in Fig. 16.

25 The caliper casting, which is movable as a unit, is mounted on stay shaft 36, being provided with depending arms 271 and 272 and webs 273 and 274, between which the shaft 265 projects. The web 274 is provided 30 with a vertical stiffening member 275. A shoe 276 is fastened to the stiffening member 275 at 277 and 278 through adjustable pin and slot connections.

The upper caliper member 264 is preferably of hardened steel and is fastened to one arm 279 of a lever which is pivoted on a pin 280, the other arm 281 of said lever being connected to an arm 282 by means of a spring 283. An adjusting screw 284 is provided to 40 adjust the position of the member 264 with relation to the lower caliper member 263. The arm 282 is preferably formed integrally with a sleeve 285 that is carried by a stub shaft 286, a gear 287 being fixedly secured to 45 said sleeve. This gear 287 meshes with a second gear 288 carried by a shaft 289. As will be observed the stub shaft 286 and the shaft 289 have bearings in the stiffening rib 275 of the caliper casting. If more than 50 one sheet endeavors to pass between the caliper elements 263 and 264, the shoe 264 will be moved toward the left as seen in Fig. 16 and, through the connections described, will rotate the gear 288 in a counterclockwise 55 direction, thus swinging a detent 290 toward the right as seen in Fig. 16, and thus moving said detent out of engagement with a pendant 291 which is pivoted on a pin 292 in one arm 293 of a bell-crank lever that is carried by shaft 289. The pendant 291 is gravity actuated to move, under these conditions, toward the right, as seen in Fig. 16, so that the tooth 294 provided at the lower end thereof will engage a ratchet wheel 295 which is mounted 60 on the continuously rotating shaft 265. Ac-

cordingly the pendant 291 will be moved downwardly, and with it the arm 293 of the bell-crank, the other arm 296 of said bell-crank being moved to the left as seen in Fig. 16. This bell-crank is operated not only to cut off the suction to the sheet separating mechanism and the forwarders, but also to elevate the drop roller. The suction is controlled by a movable disc 297 which is fixedly mounted on a stub shaft 298 (Fig. 10) which stub shaft has bearings in the side frame 32 and casting 299, said disc being mounted between the side frame 32 and said casting 299. The disc 297 is provided with an opening 300 which is normally in register at one side with 80 the suction side of the pump, and on the other side with the piping to the sheet separating mechanism and the forwarders. Movement of the arm 296 of the bell-crank operates through a link 301 which is connected at one 85 end to said arm 296 and at the other end to a pin 302 carried by said disc to move the same so that the orifice 300 therein will no longer be in register with the suction conduits, an imperforate part of the surface of the disc 90 297 being then presented to the piping that leads from the pump and also the conduits leading to the sheet separating and forwarding mechanism, with the result that the entire suction connection is broken.

95 This disc 297 is preferably provided on its periphery with a cam surface 303 which is engaged by a roller 304 carried in an arm 305 of a bell-crank lever loosely mounted on shaft 306, the other arm 307 of said bell-crank 100 lever having an adjustable connection to an arm 308 which is secured to shaft 306. To the lower end of the arm 307 there is connected a spring rod 309 that carries a spring 310 that reacts between a collar 311 secured 105 to said rod and an eyebolt 312 secured to the frame of the machine. The relation between arms 307 and 308 may be adjusted by means of the set screw 313. The arm 307 is provided with a pin 314 that engages a stop 315 110 to limit its movement toward the right as seen in Fig. 16.

115 As the disc 297 is moved toward the left, as seen in Fig. 16, the arm 307, through the connections described, will also move toward the left carrying with it the arm 308, moving the arm 308 off center sufficiently to permit a snap action of the spring 310, the effect being that the drop rollers 214 which are carried by shaft 316 mounted in arms 317 120 secured on shaft 306 will be raised out of feeding engagement with the sheets, and held in that position until the caliper mechanism is manually reset. This resetting is effected by an arm 318 mounted on shaft 298 125 which also operates to reset the disc 297 and thus again establish the suction connections from the pump to the sheet separating and forwarding devices. The disc 297 is provided with a snap-action spring similar in 130

general function to the spring 310 in that it acts to hold the disc firmly in its open or closed position. A spring rod 319 is pivoted at 320 to the disc 297 and carries a spring 321 that reacts between a collar 322 and an eyebolt 323 carried on the side frame 32 of the machine. When the lever 318 is moved to the right as shown in Fig. 16 the suction connections will be re-established through the port 300 and the snap-action spring 321 will then operate to hold the parts in this condition until the caliper is again operated. Furthermore, this movement of the lever 318 toward the right will present the low part 10 of the cam 297 to the roller 304 with the result that the weight of the drop rollers will cause the shaft 306 to be rotated in a counter-clockwise direction, thus moving the arm 308 toward the right as seen in Fig. 16 and moving the arm 307 until the pin 314 engages the stop 315, at which time the snap-action spring 20 310 will tend to hold the parts in this position.

It will be understood that this arrangement 25 in no way affects the normal raising and lowering of the drop rollers in the usual operation of the machine, inasmuch as during the normal operation the arm 308 simply moves slightly toward the right and left as seen in 30 Fig. 16 without disturbing the arm 307 or causing the spring 310 to operate.

Air and suction control, Figs. 1, 3, 4, 5, 6, 10, 16, 22 and 23

35 The air for the foot clamps 171, and the suction for the suckers 172 and the forwarders 227 are all controlled through a poppet valve arrangement which is preferable because of the fact that with poppet valves the maximum suction and air blast is secured 40 instantaneously, whereas with valves of the rotary type or of the slide type the action is progressive. A single pump 112 may be employed provided with a vacuum or suction connection 324 on one side and a wind or air blast connection 325 on the other side. Through suitable connections that will be 45 hereinafter described, the suction passes through tube 35 and through a pipe connection 326 with the valve casing. This tube 35 is provided with a plug 327 so that it constitutes in effect two tubes, one part for the suction and the other part for the air. The air passes from the tube 35 into the valve casing through pipe 328. From the valve casing the suction passes through a conduit 329 and branches 330 and 331 to the two suction pick-up devices 172. Suction also passes from the valve casing through pipe 332 and branches 333 and 334 to the forwarders 227. The air passes from the valve casing through piping 335 and branches 336 and 337 to the hollow foot clamps 171. The general piping connections are best shown in Figs. 1 and 3.

50 As here shown, the valve casing 338 is pro-

vided with a cam shaft 339 that carries four cams 340, 341, 342 and 343. Each of these cams operates a poppet valve 344, the stem of which is indicated at 345, valve spring at 346 and cam roller at 347. The cam 340 controls the suction connections to the suction pick-ups 172. The cam 341 controls the suction connections to the forwarders 227. The cam 342 controls the air connections to the hollow foot clamps 171. The cam 343 controls a valve for any auxiliary purpose that may be desired, as for blowing air in at the sides of the pile, if desired, or for any other purpose. As will be seen from Fig. 22, the cam shaft 339 carries a gear 348 that meshes 55 with a gear 349 on the main cam shaft 94.

It may be mentioned in connection with the distribution of air and suction from the pump 112 to the hollow shaft 35, that the path of the suction is through pipe 324 (see 55 Fig. 16) through casting 299, as shown in dotted lines at 350, through the disc 297, through a cored portion 351, Fig. 19, in the side frame 32, through pipes 352 and 353 and pipe 354 (Fig. 1) to the suction side of 60 the tube 35.

The air connection between the pump 112 and the hollow shaft 35 is through the pipe 325 directly into the air side of the hollow tube 35, as clearly shown in Fig. 1, wherein 65 the connection between the pipe 325 and the tube 35 is indicated at the upper left hand portion of the figure at 355.

The operation of the device is as follows:

Having first established the driving connections and the air and suction connections, and having preliminarily arranged the separator elements with respect to the wedge-shaped members 174, the separation of the sheets progresses efficiently and effectively so 100 long as there are any sheets beneath the separating elements. By means of the floating arrangement of the separator units the angle at which the separating elements operate 105 on the topmost sheet is always the same regardless of the number of sheets in the fanned-out bank, and this being so the device is equally effective regardless of the thickness of the fanned-out bank under the separator units. If desired a tail-drag 357 may be employed 110 as well as a sheet holding member 358 (Fig. 6) though in many instances these are not necessary or needed elements.

After the sheet is separated the forwarders operate to advance the successive sheets 120 to the drop rollers, and by means of the compensating arrangement on the forwarder units exact alinement of the sheets as they are presented to the feed roller and drop rollers is assured. Further, by means of the connection between the caliper and the suction control and drop rollers, the feed of the sheets will be immediately and effectively stopped if more than the predetermined 125 thickness of paper at which the caliper is set 130

is presented to the caliper rollers. This sometimes takes place when a curled or defective sheet is being fed.

It is pointed out that in continuous feeders of the prior art, there has been no preliminary separation of the sheet, the separation that has been relied on being that which has been secured by the sheet separating mechanism arranged at the advancing edge of the sheet, the customary action being the separation which is effected by the combing wheels which also act at the same time to feed the sheets, or in the suction wheel type the separation is effected by the rotary suction wheel at the same time that the sheet is fed off. By this preliminary separation, the topmost sheet of the fanned-out bank is always preliminarily and positively separated from the bank, the remainder of the bank being held against movement by the foot clamps 171 while the topmost sheet is being winded and forwarded. By these means, I have secured an efficiency and effectiveness in operation of continuous feeders that retains all of the advantages that characterize continuous feeders and with the elimination of all of the disadvantages that have also been present.

By reason of the elimination of the disadvantages that heretofore have characterized continuous feeders, and the fact that stoppages are reduced to a minimum with the present machine, the output is largely increased.

The principal advantages of my feeder over the prior art of continuous feeders are—

(1) Preliminary and positive separation of the sheets.

(2) Positive picking up of the sheets by the forwarding mechanism which insures that only one sheet at a time will be fed.

(3) Each sheet is delivered in predetermined alinement to the drop rollers or other feed off mechanism.

(4) The thickness of the bank under the separating or forwarding mechanism is immaterial to the successful operation of the mechanism.

(5) It will handle all grades, sizes, weights and quality of stock, printed or blank, that it is desired to feed without injury, smearing or smutting.

While for the purpose of illustration one embodiment of the inventive idea has been shown and described in detail, it is to be understood that the invention is not limited to the construction shown but that various expressions of the inventive idea may be had falling within the limits of the appended claims. It is to be understood that in certain installations it is not necessary to provide the forwarding mechanism with the structure for alining the sheets. It is further to be understood that with the preliminary separation of the succeeding topmost sheets of the

fanned-out bank, such accuracy and efficiency has been secured that it is possible to use only such a preliminary separating mechanism with the usual mechanism for supporting and feeding the fanned-out bank, and means for forwarding the sheet to the device to be fed. In certain installations therefore it is possible to dispense with the caliper mechanism. Further it is to be understood that while the various elements and devices have their particular application and usefulness in connection with the device such as illustrated and described, it is to be expressly understood that various of these devices have usefulness and utility in other relations, for example, in pile feeders as well as in continuous feeders.

What is claimed is:

1. In a sheet feeder, the combination of a feed board, means for fanning out and feeding a bank of sheets along said board, floating means for preliminarily separating successive sheets, a device to be fed, suction means for forwarding said preliminarily separated sheets, and means for alining the sheets as they are presented to said device. 85

2. In a continuous feeder, the combination of means for supporting and feeding a fanned-out bank of sheets and including an upper feed board and a lower feed board, devices between said feed boards for effecting a preliminary separation of succeeding topmost sheets and including laterally spaced oppositely driven combing wheels adapted to engage the topmost sheet adjacent opposite lateral edges thereof and exert a pulling action on said sheet outwardly in opposite direction, and means for automatically maintaining the separating devices in a predetermined relation to the top of the fanned-out bank regardless of the thickness of the bank, said last named means comprising a plurality of members arranged transversely of the feeder in spaced relation and resting on the fanned-out bank of sheets. 95 100

3. In a continuous feeder, the combination of means for supporting and feeding a fanned-out bank of sheets, devices for effecting a preliminary separation of succeeding topmost sheets, and means resting on the fanned-out bank and automatically maintaining the separating devices in a predetermined relation to the top of the fanned-out bank regardless of the thickness of the same. 115 110

4. In a continuous feeder, the combination of means for supporting and feeding a fanned-out bank of sheets, means for forming a valley or depression in the top of the fanned-out bank, devices for effecting a preliminary separation of succeeding topmost sheets by straightening the sheets across said valley or depression, and means for automatically maintaining the separating devices in a predetermined relation to the top of the 125 130

- fanned-out bank regardless of the thickness of the same.
5. In a continuous feeder, the combination of means for supporting and feeding a fanned-out bank of sheets, a wedge-shaped member engaging under the lateral marginal extremities of said bank, sheet separating mechanism, and a floating roller cooperating with said wedge-shaped member and automatically maintaining the separating mechanism in a predetermined relation to the top of the fanned-out bank regardless of the thickness of the same. 70
6. In a continuous feeder, the combination of means for supporting and feeding a fanned-out bank of sheets, a wedge-shaped member engaging under each lateral marginal extremity of said bank, sheet separating mechanism associated with each member, and a floating roller cooperating with each wedge-shaped member and automatically maintaining the separating mechanisms in a predetermined relation to the top of the fanned-out bank regardless of the thickness of the same. 75
7. In a continuous feeder, the combination of means for supporting and feeding a fanned-out bank of sheets, a separator unit having a relatively fixed and a relatively movable part, a roller carried by said movable part and riding on the surface of the fanned-out bank, and sheet separating mechanism carried by said movable part, said separating mechanism being maintained in a predetermined position with respect to the top of the fanned-out bank regardless of the thickness of the same. 80
8. In a continuous feeder, the combination of means for supporting and feeding a fanned-out bank of sheets, a separator unit having a relatively fixed and a relatively movable part, sheet separating mechanism carried by said movable part, and means for continuously operating said separating mechanism regardless of the thickness of the bank. 85
9. In a continuous feeder, the combination of means for supporting and feeding a fanned-out bank of sheets, a separator unit arranged at each side of the fanned-out bank, sheet separator mechanism carried by each unit, means for adjusting said separator units longitudinally of the feeder and independently of each other, and means for continuously operating said separating mechanisms regardless of the thickness of the pile and of the position of longitudinal adjustment of said separator units relatively to each other. 90
10. In a continuous feeder, the combination of means for supporting and feeding a fanned-out bank of sheets, a pair of separator units each having a relatively fixed and a relatively movable part, sheet separator mechanism carried by each movable part, means for adjusting said separator units longitudinally of the feeder and independently of each other, and means for continuously operating said separator units longitudinally of the pile and of the position of longitudinal adjustment of said separator units relatively to each other. 95
11. In a sheet feeder, the combination of means for supporting and feeding the sheets, a pair of separator units, sheet separator mechanism carried by each unit, means for adjusting said separator units longitudinally of the feeder and independently of each other, and means for continuously driving said separator mechanism regardless of their relative positions of longitudinal adjustment. 100
12. In a sheet feeder, the combination of means for supporting and feeding the sheets, a pair of separator units, sheets separator mechanism carried by each unit, means for adjusting said separator units longitudinally of the feeder and independently of each other, and means for continuously driving said separator mechanism regardless of their relative positions of longitudinal adjustment, including a differential gearing interposed between said separator units. 105
13. In a sheet feeder, the combination of a sheet support, a device to be fed, suction forwarding means for feeding successive sheets to said device, a rectilinearly reciprocating member carrying the suction forwarding means, and means automatically controlling the reciprocating and forwarding movements of said member and the suction forwarding means respectively for alining the sheets with respect to the device to be fed. 110
14. In a sheet feeder, the combination of a sheet support, a device to be fed, a pair of suction means for feeding successive sheets to said device in predetermined alinement, a pair of rectilinearly reciprocating members carrying one of said suction means, and means associated with each reciprocating member for controlling the effective feeding movement of the suction means carried thereby. 115
15. In a continuous sheet feeder, the combination of a sheet support, a device to be fed, forwarding means for feeding successive sheets to said device, a track or support, a carriage reciprocating rectilinearly along the track or support and carrying said forwarding means, and means automatically controlling the reciprocating and feeding movements of the carriage and the forwarding means respectively for alining the sheet with respect to the device to be fed. 120
16. In a sheet feeder, the combination of a sheet support, means for feeding a fanned-out bank of sheets along said support, a device to be fed, a forwarding device arranged on either side of the medial longitudinal line of the sheet, and adapted to be reciprocated rectilinearly and moved toward and away from the sheet support and means in the path of the sheet automatically controlling the 125
- 130

reciprocating movement of the forwarders for alining the sheet with respect to the device to be fed.

17. In a sheet feeder, the combination of a sheet support, means for feeding a fanned-out bank of sheets along said support, a device to be fed, a forwarding device arranged on either side of the medial longitudinal line of the sheet, a track or the like for each forwarding device and along which the same is reciprocated, pendulum means in the path of the sheet and associated with each forwarding device, and stop mechanism for each forwarding device operable when the sheet engages said pendulum means, whereby the sheet is brought into predetermined alinement with respect to the device to be fed.

18. In a sheet feeder, the combination of a sheet support, a device to be fed, a forwarding device arranged on either side of the medial longitudinal line of the sheet, means in the path of the sheet automatically controlling the feeding movement of the forwarders for alining the sheet with respect to the device to be fed, a pair of tracks or the like on which the forwarders are mounted, and means for reciprocating said forwarders rectilinearly along said tracks including a lost motion connection whereby the last named means may continue to move after either of the forwarders have stopped.

19. In a sheet feeder, the combination of a sheet support, a device to be fed, a forwarding device for the sheet, means in the path of the sheet for controlling the feeding movement of the forwarder, a track or the like on which the forwarder is mounted, and means for reciprocating said forwarder rectilinearly along said track including a lost motion connection whereby the last named means may continue to move after the forwarder has stopped.

20. In a sheet feeder, the combination of means for supporting and feeding a fanned-out bank of sheets, suction means for effecting a preliminary separation of the sheets, suction means for forwarding the sheets to the device to be fed, poppet valves controlling the application of suction to said means, and mechanism for reciprocating said valves to open and close the same at predetermined intervals.

21. In a sheet feeder, the combination of means for supporting and feeding a fanned-out bank of sheets, suction means for effecting a preliminary separation of the topmost sheet, a foot clamp for holding the remainder of the bank while said sheet is being wended by said foot clamp, suction forwarding means for delivering the sheet so preliminarily separated, poppet valves controlling the application of suction to said means and the application of air to said foot clamp, and mechanism for reciprocating said valves to open and close the same at predetermined intervals.

22. In a sheet feeder, the combination of sheet supporting means, sheet separating and forwarding means, a source of suction, a valve housing, connections between the source of suction and the valve housing and between the latter and the sheet separating and forwarding means, poppet valves in said housing and controlling the suction in said sheet separating and forwarding means, and mechanism for reciprocating said poppet valves to open and close the same at predetermined intervals.

23. In a sheet feeder, the combination of sheet supporting means, sheet separating and forwarding means, a nozzle or the like through which air is blown to assist in separation of the sheets by the sheet separating means, a source of air and suction, a valve housing, connections between said source and said housing and between the latter and the sheet separating means, the sheet forwarding means, and said nozzle, poppet valves in the housing and controlling the suction and air in the separating and forwarding means and the nozzle respectively, and mechanism for reciprocating said poppet valves to open and close the same at predetermined intervals.

24. In a sheet feeder, the combination of sheet supporting means, sheet separating and forwarding means, a source of suction, a valve housing, connections between the source of suction and the valve housing and between the latter and the sheet separating and forwarding means, poppet valves in said housing and controlling the suction in said sheet separating and forwarding means, a driven shaft, and a plurality of cams secured on said shaft and adapted to reciprocate said poppet valves to open and close the same at predetermined intervals.

25. In a sheet feeder, the combination of sheet supporting means, sheet separating and forwarding means, a nozzle or the like through which air is blown to assist in separation of the sheets by the sheet separating means, a source of air and suction, a valve housing, connections between said source and said housing and between the latter and the sheet separating means, the sheet forwarding means, and the nozzle, poppet valves in the housing and controlling the suction and air in the separating and forwarding means and said nozzle respectively, and a plurality of driven cams engaging the stems of said valves and adapted to reciprocate the valves and open and close the same at predetermined intervals.

26. In a sheet feeder, the combination of sheet supporting means, sheet separating and forwarding means, a nozzle through which air is blown to assist separation of the sheets by the sheet separating means, a conduit closed intermediate the opposite ends thereof, a source of air connected with one side of the conduit, a source of suction connected

with the other side of the conduit, a valve housing communicating with both sides of said conduit and with the separating and forwarding means and said nozzle, a plurality of poppet valves arranged in said housing to control the suction in the separating and forwarding means and the air in the nozzle, and mechanism for reciprocating said valves to open and close the same at predetermined intervals.

27. In a sheet feeder, the combination of a support on which a fanned-out bank of sheets is fed, means adapted to engage the fanned-out bank of sheets on the top and bottom thereof and form a valley or depression therein, and means for separating the sheets including devices adapted to engage each sheet adjacent opposite sides thereof and exert a pulling action on said sheet outwardly in opposite directions across said valley or depression.

28. In a sheet feeder, a support on which a fanned-out bank of sheets is fed, normally stationary means engaging the bank of sheets on the under side thereof, rotary means engaging the bank of sheets on the upper side thereof and cooperating with said first named means to form a valley or depression in said bank of sheets, and means for separating the sheets including a pair of rotary members adapted to engage each sheet adjacent opposite sides thereof and exert a pulling action on said sheet outwardly in opposite directions across said valley or depression.

29. In a sheet feeder, a support on which a fanned-out bank of sheets is fed, means for separating the sheets comprising a suction device movable toward and away from the same, a stationary member and a rotatable member adjacent each side of the bank of sheets and adapted to form a valley or depression therein, and means for straightening each sheet across said valley or depression before it is separated by said suction device.

30. In a sheet feeder, a feed board on which a fanned-out bank of sheets is fed, means for forming a valley or depression in the fanned-out bank of sheets and comprising relatively stationary and movable devices between which said fanned-out bank of sheets is engaged while being fed along said feed board, means for straightening the sheets across said valley or depression, and means for separating said sheets successively from said bank.

31. In a sheet feeder, spaced stationary devices engaging a fanned-out bank of sheets on one side thereof, and spaced rotatable devices engaging said fanned-out bank of sheets on the opposite side thereof and cooperating with said stationary devices to form a valley or depression in the fanned-out bank of sheets.

32. In a sheet feeder, spaced oppositely inclined stationary devices engaging a fanned-

out bank of sheets at one side thereof, and spaced oppositely inclined rotatable devices engaging said fanned-out bank of sheets at the opposite side thereof and cooperating with said stationary devices to form a valley or depression in the fanned-out bank of sheets.

33. In a sheet feeder, a support along which a fanned-out bank of sheets is fed, and means at each side of the fanned-out bank of sheets adapted to form a valley or depression therein and comprising relatively stationary and rotatable devices having opposed inclined surfaces between which the fanned-out bank of sheets is engaged while being fed along said feed board.

34. In a sheet feeder, means for feeding a fanned-out bank of sheets, and means for forming a valley or depression in the fanned-out bank of sheets and comprising spaced members engaging said fanned-out bank of sheets on the top and bottom thereof as the same is fed by said feeding means.

35. In a sheet feeder, means for feeding a fanned-out bank of sheets, and means for forming a valley or depression in the fanned-out bank of sheets and comprising spaced stationary members having side guides therefor and upwardly and outwardly inclined surfaces over which said fanned-out bank of sheets is fed by said feeding means.

36. In a sheet feeder, means for feeding a fanned-out bank of sheets, and means for forming a valley or depression in the fanned-out bank of sheets and comprising normally stationary members arranged under and engaging said fanned-out bank of sheets adjacent lateral marginal portions thereof, and means for adjusting said member toward and away from each other as desired.

37. In a sheet feeder, the combination of an upper feed board and a lower feed board along which a fanned-out bank of sheets is fed, means for forming a valley or depression in the fanned-out bank of sheets and including normally stationary devices mounted on said lower feed board and engaging said fanned-out bank of sheets, means for effecting a preliminary separation of a sheet and including laterally spaced oppositely driven combing wheels arranged between said feed boards to engage the sheet adjacent opposite lateral edges thereof and exert a pulling action on the sheet outwardly in opposite directions to straighten it across said valley or depression, and means for finally separating and feeding said sheet from the feeder.

38. In a sheet feeder, the combination of a feed board, means for feeding a fanned-out bank of sheets along said feed board, means for forming a valley or depression in the fanned-out bank of sheets and including normally stationary devices engaging said fanned-out bank of sheets during the feeding of the same along the feed board, means for

- effecting a preliminary separation of a sheet and including laterally spaced oppositely driven combing wheels adapted to engage the sheet adjacent opposite lateral edges thereof and exert a pulling action on the sheet outwardly in opposite direction to straighten it across said valley or depression, a device to be fed, and forwarding means for finally separating and advancing said sheet to said device. 70
39. In a sheet feeder, the combination of a feed board, means for fanning out and forming a valley or depression in a bank of sheets on the feed board and including spaced normally stationary devices carried thereby, means for effecting a preliminary separation of a sheet by straightening it across said valley or depression and including laterally spaced oppositely driven combing wheels arranged to engage the sheet adjacent opposite lateral edges thereof and exert a pulling action on the sheet outwardly in opposite directions, and suction means for finally separating and forwarding said sheet. 75
40. In a sheet feeder, the combination of a feed board along which a fanned-out bank of sheets is fed, means for forming a valley or depression in the fanned-out bank of sheets and including normally stationary devices mounted in spaced relation on said feed board and engaging lateral marginal portions of said fanned-out bank of sheets at the underside thereof, means for effecting a preliminary separation of a sheet and including floating laterally spaced oppositely driven combing wheels arranged to engage the sheet adjacent opposite lateral sides thereof and exert a pulling action on said sheet outwardly in opposite directions to straighten it across said valley or depression, a device to be fed, and means for finally separating and forwarding sheets so preliminarily separated to the device to be fed. 95
41. In a sheet feeder, the combination of an upper feed board and a lower feed board along which a fanned-out bank of sheets is fed, means for effecting a preliminary separation of a sheet and including oppositely driven combing wheels arranged between said feed boards to engage adjacent opposite lateral margins thereof and exert a pulling action on the sheet outwardly in opposite directions, and means for finally separating said sheet and feeding it from the feeder. 105
42. In a sheet feeder, the combination of a feed board, means for feeding a fanned-out bank of sheets along said board, means for effecting a preliminary separation of a sheet and including oppositely driven combing wheels arranged to engage the sheet adjacent opposite lateral margins thereof and exert a pulling action on the sheet outwardly in opposite directions, a device to be fed, and forwarding means for finally separating said sheet and advancing it to said device. 120
43. In a sheet feeder, the combination of a feed board, means for fanning out a bank of sheets thereon, suction and mechanical means for effecting a preliminary separation of a sheet and including oppositely driven combing wheels arranged to engage the sheet adjacent opposite lateral margins thereof and exert a pulling action on said sheet outwardly in opposite directions, and suction means for finally separating and forwarding the sheet. 125
44. In a sheet feeder, the combination of a feed board along which a fanned-out bank of sheets is fed, means for effecting a preliminary separation of a sheet and including floating oppositely driven combing wheels arranged to engage the sheet adjacent opposite lateral sides thereof and exert a pulling action on said sheet outwardly in opposite directions, a device to be fed, and means for finally separating and forwarding successive sheets so preliminarily separated to said device. 130

In testimony whereof I have signed this specification.

EDWARD R. KAST. 90
